UNITED STATES PATENT OFFICE.

JOHN W. CLARK, OF HAMILTON, OHIO.

WAGON-JACK.

SPECIFICATION forming part of Letters Patent No. 414,678, dated November 12, 1889.

Application filed August 28, 1889. Serial No. 322,170. (No model.)

To all whom it may concern:

Be it known that I, JOHN W. CLARK, of Hamilton, Butler county, Ohio, have invented certain new and useful Improvements in 5 Wagon-Jacks, of which the following is a specification.

This invention pertains to certain improvements in the construction of jacks designed for elevating and supporting wagon-axles 10 when the wheels are to be removed, &c.

My improvements will be readily understood from the following description, taken in connection with the accompanying drawings, in which—

15 Figure 1 is a front elevation of a wagon-jack embodying my improvements; Fig. 2, a rear elevation of the main portions of the same; Fig. 3, a horizontal section of the same in the plane of the axis of the lever-pivot; 20 Fig. 4, a horizontal section in the same plane, but upon a very much enlarged scale, of the parts contiguous to the lever-pivot; Fig. 5, a perspective view of the front of the ratchet-plate, and Fig. 6 a perspective view of the 25 pawl shown in position in a portion of the lever-shank.

In the drawings, A indicates a base-piece or foot; B, an upright board secured at its lower end to the base-piece; C, braces at the foot of 30 the upright connecting the upright and base-piece; D, a ratchet-plate bolted against the front face of the upper end of the upright; E, ratchet-teeth projecting from the periphery of the ratchet-plate, these teeth extending 35 around a portion only of the periphery of the plate; F, a lever-shank in the form of a plate lying against the side of and pivoted to the ratchet-plate, this lever-shank projecting out to the left to form a lever end to engage the 40 axle to be lifted, while its projection to the right is formed to receive a wooden hand-lever; G, a hand-lever bolted to the lever-shank, whereby the lever-shank and lever become virtually a single lever-piece pivoted to the 45 ratchet-plate; H, a pivot-bolt uniting the lever-shank to the ratchet-plate; J, a box-like projection from the rear face of the lever-shank at that portion of the lever-shank where the hand-lever is secured, this box-like 50 projection forming a pawl-guide by having in each end wall a hole in which a pawl fits and

slides; K, a pawl in the form of a square bar sliding through the holes in the end walls of the box-like projection; the pawl thus passing entirely through the box-like projection 55 and having its inner end formed to engage properly with the teeth of the ratchet-plate; L, a spring coiled around the pawl within the box-like projection, one end of the spring abutting against the inner surface of the 60 outer end wall of the box-like projection, while the other end of the spring abuts against a pin put transversely through the pawl, the spring thus tending to urge the pawl into engagement with the teeth of the ratchet-plate; 65 M, a finger-lever pivoted at the outer end of the hand-lever and adapted to be vibrated by the hand in grasping the end of the hand-lever; N, a pawl-rod lying along the rear face of the hand-lever, and connected at one end 70 with the finger-lever end and at the other end with the pawl, whereby by elevating the finger-lever the pawl may be moved outward against the resistance of its spring; O, a very large washer upon the pivot-bolt H, and held 75 by that bolt against the front face of the lever-shank, the lever-shank thus being loosely clamped between the ratchet-plate and this washer; and P, a boss formed upon the front face of the ratchet-plate and projecting therefrom into an appropriate pivot-aperture in the lever-shank, the boss thereby forming a pivot 80 on which the lever-shank rocks and which supports the lever-shank, while the pivot-bolt and flange serve as means for preventing the 85 side displacement of the lever-shank from the boss and for securing side steadiness in the motion.

The pivot-bolt may, if desired, be drawn so tight as to frictionally clamp the lever-shank, 90 so that the lever will be sustained in any position in which it may be placed, thus avoiding the accidental dropping of the lever, and also permitting of the lever being placed directly vertical, so that the device may, when 95 not in use, stand in a small space. When the device is to be used, the lever is placed in a horizontal position with the left end of the lever-shank under the axle to be elevated. The handle end of the lever is now depressed, 100 thus elevating the axle, and the spring throws the pawl into engagement with the appropri-

ate ratchet-tooth, and the load will be sustained. When the load is to be lowered, the hand is placed upon the handle of the hand-lever and the finger-lever is pulled upward by 5 the fingers of the hand, thus withdrawing the pawl and permitting the hand-lever to rise and the load to go down.

I claim as my invention—

In a wagon-jack, the combination, substantially as set forth, of a base-piece, an upright secured thereto, a ratchet-plate secured against the face of the upper end of the upright, and having ratchet-teeth projecting from its periphery, and having a pivot-boss 10 projecting from its outer face, a lever-shank pivoted on said pivot-boss and against the face of the ratchet-plate, and having projec-

tions adapted to engage a wagon-axle and to receive a hand-lever, respectively, and provided upon its face with a box-like projection, 20 a bolt clamping said lever-shank against said ratchet-plate, a pawl fitted to slide in the end walls of said box-like projection and to engage the teeth of the ratchet-plate, a spring upon said pawl arranged to press the pawl 25 into engagement with the teeth of the ratchet-plate, a hand-lever secured to the lever-shank, a finger-lever pivoted at the end of the hand-lever, and a pawl-rod connected with the finger-lever and pawl.

JOHN W. CLARK.
